SAFETY OIL CAN

Joseph E. Schlorff, Pesotum, III.

Application October 29, 1931. Serial No. 571,876

5 Claims. (Cl. 220—75)

This invention has for one of its objects to eliminate all danger of persons catching fire as the result of carelessly using cans containing explosive oils about or near fires. Accidents of this nature, which take an astonishing toll of life annually, occur most frequently as the result of pouring oil on fires from cans having the upright seams of their bodies located at their rear sides. The location of the upright body seams at the rear sides of the cans, which is a characteristic feature of all oil cans now on the market, causes the bodies, when the contents of the cans explode, to open at their rear or those sides facing the users, with the result that the burning contents are sprayed over and set the users on fire.

To overcome the stated objection to the present type of oil cans, and thus eliminate all danger of persons catching fire as a result of the explosion of the cans, my invention comprehends the provision of an oil can which will have the upright seam of its body located at its front or that side thereof facing away from the user, to the end that on the explosion of the can the flaming contents thereof will be directed away from and not in the direction of the user.

My invention has for a further object to provide a can of the character stated wherein the body will be connected to the bottom and head in such manner that portions of the body near and at opposite sides of the front upright seam will become detached from the bottom and head when the contents of the can explodes, to the end that the bottom and head will not be displaced and thus further insure the spraying of the burning contents away from and not in the direction of the user.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a view partly in side elevation and partly in vertical section of an oil can constructed in accordance with my invention;

Figure 2 is a sectional view taken on the horizontal planes indicated by the line 2—2 of Figure 1;

Figure 3 is a detail sectional view taken on the horizontal plane indicated by the line 3—3 of Figure 1, and

Figure 4 is a top plan view of a fragmentary portion of the bottom of the can.

55 The oil can comprises a body 1, bottom 2 and

head 3. The head 3 is provided with a filler nipple 4 which is closed by a cap 5 screw threadedly engaged therewith. A handle 6 is pivotally secured, as at 7, to the body 1. A spout 8 is carried by the head 3 forwardly of the filler nipple 4 60 and extends in an upward and forward direction from the head.

The body 1 is made from a single blank of sheet metal, and the upright edges thereof are connected by a seam 9 which extends throughout the entire height of the body and which consists of a U-shaped member 9a and a tongue 9b. The seam member 9a which is formed integrally with one upright edge of the body 1 lies in contact with the outer surface of the body, and has its open side arranged in facing relation to the other upright edge of the body. The seam tongue 9b which is formed integrally with the other free edge of the body 1, is offset outwardly from the body, and extends into the seam member 9a 75 through the open side thereof. The seam members 9a and 9b are secured in assembled relation by soft solder 10. The seam members 9a and 9b are so related to the upright edges of the body 1 and to each other that they may be separated by 80 a force within the body 1 acting in a direction to separate the upright edges of the body and of sufficient strength to overcome the connection of the seam members by the solder 10 and the connection of the body with the bottom 2 and 85 head 3.

The bottom 2 and the head 3 are also made from sheet metal, the former being provided at its periphery with an upstanding annular flange 11, and the latter being provided at its periphery 90 with a depending annular flange 12. The bottom flange 11 consists of semi-circular rear and front portions 11a and 11b, respectively, and the top flange 12 consists of semi-circular rear and front portions 12a and 12b, respectively. The front 95 flange portion 11b occupies an inwardly spaced concentric position with relation to the rear flange portion 11a, and the front flange portion 12b occupies a similar position with relation to the rear flange portion 12a.

The lower edge portion of the rear half of the body 1 is located inwardly of and contacts with the rear flange portion 11a, and the lower edge portion of the front half of the body is located outwardly of and contacts with the front flange 100 portion 11b. The upper edge portion of the rear half of the body 1 is located inwardly of and contacts with the rear flange portion 12a, and the upper edge portion of the front half of the body is located outwardly of and contacts with the front flange 105 portion 11b. The lower edge portion of the rear half of the body 1 is located inwardly of and contacts with the rear flange portion 11a, and the lower edge portion of the front half of the body is located outwardly of and contacts with the front flange 110 portion 11b.

front flange portion 12b. The body 1 is secured to the flange portions 11a and 12a by hard solder 13, and the body is secured to the flange portions 11b and 12b by soft solder 14.

5 As the lower and upper edges of the front half of the body 1 are located outwardly of the front flange sections 11b and 12b and are secured to these sections by soft solder, the generation within the body of a force sufficient to overcome the connection between the seam members 9a and 9b and the connection between the body and the flange portions 11b and 12b will move the body away from the bottom 2 and head 3. It will thus be seen that, should the contents of the can ignite while being poured on a fire for the purpose of quickening the same, the resulting pressure generated within the can will, when great enough to burst the same, open the front side of the body 1 to cause the flaming contents to be sprayed away from and not in the direction of the user, thus eliminating all possibility of the user catching fire. The detached front portions of the body 1 will spread laterally, as suggested by dotted lines in Figure 2, and provide guards adapted to direct the flame away from the user. The bottom 2 and head 3 which will not become detached from the body 1 due to the fact that the body is connected to the inner sides of their rear flange portion by hard solder, will also constitute guards tending to direct the flame away from the user.

10 15 20 25 30 35 40 45 50

30 From the foregoing description, taken in connection with the accompanying drawing, it should be apparent that the can embodies a construction which will positively eliminate all danger of persons catching fire as the result of carelessly using the can about or near fires, and that the can is simple and durable and capable of being manufactured and sold at a comparatively low cost.

40 While I have described the principle of the invention, together with the structure which I now consider the preferred embodiment thereof, it is to be understood that the structure shown is merely illustrative and that such changes may be made, when desired, as fall within the scope 45 of the invention as claimed.

What is claimed is:—

1. An oil can including a bottom having an upwardly directed annular flange, a head having a downwardly directed annular flange, and a body having a single upright seam located at the

front side of the can and having its rear half secured to the inner side of said flanges by hard solder and having its front half secured to the outer sides of said flanges by soft solder.

5 10 15 20 25 30 35 40 45 50 55 60 65 70 75 80 85 90 95 100 105 110 115 120 125 130 135 140 145 150

2. An oil can including a bottom having an upwardly directed annular flange, a head having a downwardly directed annular flange, and a body provided solely at its front side with seam members connected by soft solder, the body having its rear half connected to the inner sides of said flanges by hard solder and having its front half connected to the outer sides of said flanges by soft solder.

3. An oil can including a bottom having an upwardly directed flange, a head having a downwardly directed flange, each of said flanges consisting of semi-circular rear and front portions with the front portions arranged in inwardly spaced concentric relation to the rear portions, and a body provided solely at its front side with seam members connected by soft solder, the rear half of the body being located inwardly of and secured by hard solder to said rear flange sections, and the front half of the body being located outwardly of and secured by soft solder to said front flange sections.

4. An oil can comprising a cylindrical body, a bottom secured to one end of the body, a top secured to the other end of the body, a spout carried by the top, a relatively weak means for securing a portion of the top to the body whereby to permit separation of said portion from the body under abnormal pressure within the body, and a relatively strong securing means for securing the remaining portion of the top to the body, said second securing means holding the remaining top portion against separation under abnormal pressure.

5. An oil can comprising a body open at each end, end members for said body, a relatively strong means for securing a portion of certain of said end members to the body against separation under abnormal pressure of the contents of the body, and a relatively weak securing means for securing the remaining portion of said certain end members to the body in a manner to permit separation of said certain end members from the body under abnormal pressure within the body.
